UNITED STATES PATENT OFFICE.

CHARLES P. MADSEN, OF CHICAGO, ILLINOIS.

ELECTRICALLY-HEATED FLAT-IRON.

1,122,521.

Specification of Letters Patent. Patented Dec. 29, 1914.

Application filed April 3, 1912. Serial No. 688,224.

To all whom it may concern:

Be it known that I, CHARLES P. MADSEN, a citizen of the United States of America, and a resident of Chicago, Cook county, Illinois, have invented certain new and useful improvements in Electrically-Heated Flat-Irons, of which the following is a specification.

The main objects of this invention are to provide an improved form of electrically heated flatiron, having comparatively few parts, all of which are of simple construction and which are capable of being quickly and cheaply made; to provide an improved construction of the interfitting faces of said parts; to provide improved construction and arrangement of the heating unit in the iron; to provide simple and improved means for securing the parts of the iron in their assembled positions; to provide improved means for securing the heating unit in the iron; to provide improved means for connecting the conductors to the heating unit; and to provide improved means for supporting the conductor cords adjacent to the iron.

An illustrative embodiment of this invention is shown in the accompanying drawings, in which:

Figure 1 is a longitudinal sectional elevation of an electrically heated flatiron constructed according to this invention the section being taken on the line A—A of Fig. 2. Fig. 2 is an enlarged transverse sectional elevation of the same taken on the line B—B of Fig. 1. Fig. 3 is a top plan view of the base showing the arrangement of the resistance ribbon therein, the insulating compound being omitted. Fig. 4 is a fragmentary detail, as viewed from below, of one point of the body member.

In the construction shown in the drawings, the flatiron comprises the base member 1, in which the heating unit 2 is housed, and the body member 3 secured to the base member 1 by means of the stud 4 and nut 5. The base and body members are respectively provided with triangularly shaped interfitting lugs 1^A and notches 3^A at both ends which coact to secure the members against shifting when clamped together.

The base member 1 has the inner part recessed nearly co-extensively with the area thereof whereby there is provided an upward standing flange 6 around the entire outer edge of the member. The heating unit 2,

which is housed within the recess, comprises resistance ribbon 7 arranged as shown and embedded in an insulating body or compound 8, preferably of the kind which when moist is plastic, and when the moisture evaporates becomes hard. This compound is comparatively friable and necessitates means for firmly securing the heating unit within the recess. In electrically heated irons heretofore equipped with heating units in which the resistance ribbon or wire is embedded in an insulating compound of this nature, no suitable means have yet been provided for properly securing the unit within the iron and protecting the insulating compound. In this device the heating unit 2 is secured within the recess in the base member 1 by means of an insulating pad 9 which is of rigid construction, and preferably formed of asbestos. The pad is substantially similar in shape and co-extensive in area to the recess in the base 1 and therefore bears directly upon the entire face of the insulating compound 8 of the heating unit as shown in Figs. 1 and 2. The pad is secured at its center and caused to bear upon the heating unit by means of a nut 10 and washer 11 placed upon the stud 4. The body member 3 is also recessed to provide a downwardly disposed flange 12 extending around the outer edge thereof, and also to provide an internal shoulder 13 extending around the interior of the body which bears upon the edge of the pad 9, when the body member 3 is clamped to the base member 1, thereby causing the pad to more firmly bear upon the heating unit 2, and hold it under pressure.

Heretofore considerable difficulty has been encountered in electrically heated flatirons in the deterioration of the connections between the conductors and the resistance ribbon or wire of the heating unit. If the resistance wire is run to the top of the iron and connected directly with the conductors, heat will be generated at the top surface of the iron, and in time will destroy the copper at and adjacent to the connection. If, on the other hand, the conductors be run down through the flatiron and connected into the heating unit, the effect is still worse, since the high temperature in the heating unit has a still greater tendency to destroy the copper. Attempts have been made to overcome these disadvantages by the use of an intermediary conductor of some alloy or other metal interposed between the resist-

ance wire of the heating unit and the conductors, but whether such a joint be mechanical or soldered, the same conditions exist to a more or less extent. All of these disadvantages are satisfactorily overcome by means of the connection which is illustrated in the accompanying drawings. This connection is made between the respective ends of the resistance ribbon 7 and the copper wires 17 of the conductor cords 18 within the rigid insulating tubes 14. The tubes 14 are preferably constructed of asbestos and extend into the body member 3 and through the pad 9 to the heating unit, as shown in Fig. 2. The ends of the resistance ribbon 7 are led up through the respective tubes to the copper wires 17, and the ends of the ribbon and wire overlapped. Auxiliary conductors 19 are used in completing each of the connections of the resistance wires and the conductors. One end of an auxiliary conductor 19 is coiled closely around the overlapping ends of the resistance ribbon 7 and copper wire 17. This auxiliary conductor 19 is then spirally wound around the resistance ribbon 7 down through the tube into the heating unit and the lower end thereof coiled closely around the resistance ribbon, as indicated at 20 in Fig. 2. The auxiliary conductors are of considerably greater conductivity than the resistance ribbon 7 and at the same time possess sufficient resistance power to the heat generated by the heating unit. The joints are then hard soldered at the said closely coiled ends of the auxiliary conductor 19 and it is evident that should either of the joints fail there will still be conductivity through the other.

40 A handle 21 has a yoke 22 which is provided with a suitable aperture 23 whereby the yoke is adapted to rest upon the top of the body member 3 with the stud 4 protruding through said aperture, the yoke being secured to said body member and stud by means of the nut 5.

45 A conductor cord support is arranged for supporting the conductor cords 18 adjacent to the iron. This support comprises an arm 50 24 at the upper end of which is formed a yoke 25 adapted to embrace the conductor cords 18. The lower end of the arm 24 is bent at an angle and provided with an aperture 26 whereby it may be placed over the stud 4 above the yoke 22 of the handle 21, and rigidly secured to the iron by means of the nut 5, a washer 27 being interposed between the nut 5 and arm 24. A depending lug or shoulder 24' bears against the yoke 22 and secures the support against shifting.

55 60 A helical spring 28 embraces the conductor cords 18 adjacent to the support and prevents excessive bending of the conductor cords.

The operation of the device is, of course,

obvious and a description thereof need not be recited.

Although but one specific embodiment of this invention has been herein shown and described, it will be understood that numerous details of the construction shown may be altered or omitted without departing from the spirit of this invention as defined by the following claims.

I claim:—

1. In an electrically heated flatiron, the combination of a base member having the inner part thereof recessed; a heating unit embedded in an insulating compound and housed in said recess; a body member; rigid means for clamping said body member to said base member, and other rigid means overlying said heating unit and actuated through the clamping of said body member to said base member for securing said heating unit in said recess. 75

2. In an electrically heated flatiron, the combination of a base member having the inner part thereof recessed nearly co-extensively with the area thereof; a heating unit embedded in an insulating compound and housed in said recess; a body member; rigid means for clamping said body member to said base member; and other rigid means actuated by and through said body member 90 when the latter is clamped to said base member for securing said heating unit in said recess. 95

3. In an electrically heated flatiron, the combination of a base member having the inner part thereof recessed; a heating unit embedded in an insulating compound and housed in said recess; a body member; a central stud and coating means arranged for clamping said body member to said base member; a rigid insulating pad similar in shape and substantially equal in area to said recess; a nut intermediately positioned on said stud and arranged to be screwed down upon said pad centrally thereof; and shoulders on said body member adapted to bear upon said insulating pad when said members are clamped together, for securing said heating unit in said recess. 100 105

4. In an electrically heated flatiron, the combination of a base member and a body member adapted to be clamped together; a heating unit housed within said member, said heating unit comprising resistance wire embedded in an insulating compound; an insulating tube extending from said heating unit to the exterior of said iron; electric conductors adapted to be connected to the source of electricity; the ends of said resistance wire extending through said tubes from said heating unit and respectively joined to said conductors, and an auxiliary conductor extending through each of said tubes and respectively connected at its ends to said resistance wire within said heating unit and to 115 120 125 130

the juncture of said circuit conductors and resistance ribbon.

5. In an electrically heated flatiron, the combination of a base member and a body member adapted to be clamped together; a heating unit housed within said members, said heating unit comprising resistance wire embedded in an insulating compound; an insulating tube extending from said heating unit to the exterior of said iron; electric conductors adapted to be connected to the source of electricity; the ends of said resistance wire extending through said tubes from said heating unit and respectively joined to said conductors; and an auxiliary conductor of relatively different conductivity and heat endurance extending through each of said tubes and respectively connected at its ends to said resistance wire within said heating unit and to the juncture of said circuit conductors and resistance ribbon.

20

6. In an electrically heated flatiron, the combination of a base member and a body member adapted to be clamped together; a heating unit housed within said members, said heating unit comprising resistance wire embedded in an insulating compound; an insulating tube extending from said heating unit to the exterior of said iron; electric conductors adapted to be connected to the source of electricity; the ends of said resistance wire extending through said tubes from said heating unit and respectively joined to said conductors; and an auxiliary conductor

35

40

coiled about said resistance wire in each of said tubes and having the ends thereof respectively connected to the resistance wire within said heating unit and to the juncture of said circuit conductors and resistance ribbon.

7. In an electrically heated flatiron, the combination of a base member; a heating unit housed within said base member; a body member adapted to be secured to said base member; a stud centrally located on said base member and protruding to the exterior of said body member; means on said stud for clamping said body member to said base member; conductor cords adapted to be connected to said heating unit, and a support for said conductor cords comprising an arm having a yoke at its upper end embracing said cords and having its lower part shaped to engage said stud inward of said clamping means.

45

50

55

8. In an electrically heated flatiron, the combination of a base member having a heating unit housed therein, a body member formed to fit upon said base member and having a central perforation, a handle for said iron having a part thereof resting upon said body member and provided with an aperture in registry with the said body perforation, a stud centrally located on said body member and protruding through the said perforation and aperture, and a nut carried by said stud and adapted to simultaneously clamp said handle to said body member and said body member to said base member.

9. In an electrically heated flatiron, the combination of a base member; a heating unit housed within said base member; a body member adapted to be secured to said base member; a stud centrally located on said base member and protruding to the exterior of said body member; a handle for said iron having a part thereof resting upon said body member and provided with an aperture for receiving said stud; and a nut carried by said stud and adapted to simultaneously clamp said handle to said body member and said body member to said base member; conductor cords adapted to be connected to said heating unit, and a support for said conductor cords comprising an arm having a yoke at its upper end embracing said cords and having its lower part shaped to engage said stud inward of said nut.

10. In a device of the class described, a base member having an upwardly projecting stud thereon and substantially integral therewith, a body member formed to fit upon said base member and perforated to receive said stud, a handle member having an apertured portion arranged to lie closely against the upper side of the member with its aperture in alignment with said stud to receive the same, and means coacting with said stud for forcing said handle member and body member tightly together against said base member for holding said parts together.

Signed at Chicago this 27th day of March 1912.

CHARLES P. MADSEN.
